UNITED STATES PATENT OFFICE.

JOHN RIDDELL, OF SCHENECTADY, NEW YORK, ASSIGNOR TO GENERAL ELECTRIC COMPANY,
A CORPORATION OF NEW YORK.

MILLING-MACHINE.

No. 910,315.

Specification of Letters Patent.

Patented Jan. 19, 1909.

Application filed April 17, 1905. Serial No. 255,880.

To all whom it may concern:

Be it known that I, JOHN RIDDELL, a citizen of the United States, residing at Schenectady, county of Schenectady, State of New York, have invented certain new and useful Improvements in Milling-Machines, of which the following is a specification.

My invention relates to metal working machines, and relates more particularly to a machine for finishing the buckets of elastic fluid turbines, although it is not limited in all respects to this use.

Buckets for elastic fluid turbines as heretofore constructed have been provided with curved walls or surfaces which merge into flat tangential surfaces that direct the passage of motive fluid, and it is to the finishing of these tangential surfaces that this invention more specifically relates. Hitherto it has been found necessary to do this by hand. Obviously, this is a slow and expensive operation, requiring a large number of hands for the work and a considerable outlay for files. Moreover, hand-work is to a greater or less extent inaccurate and ununiform; this being highly objectionable because it directly affects the economy of operation of the turbines.

The object of my machine is to supersede hand-work, as to a large part of the finishing operation, so as to improve the quality of the work and to increase production.

The machine is adapted more especially for finishing the flat end surfaces of the front of the buckets, or those surfaces which extend tangentially to and on opposite sides of the central curved portion. The buckets, as made in a bucket-cutting machine or by casting, are more or less rough, and the flat surfaces may not at times have the proper angle so that they require to be finished. The finishing is an important operation, as the efficiency of the turbine depends to a considerable degree upon the smoothness of the surfaces and the uniformity of their angle relatively to the direction of the jets of the working fluid from the nozzles.

In carrying out the invention, the milling machine and the bucket-wheel or other work to be finished, may be so arranged relatively to each other that either may be moved progressively to bring the buckets and cutter together as the finishing operation proceeds. The machine comprises a

column, a radial arm extending therefrom and mounted with respect thereto to permit of a relative turning movement, a cutter and a carriage therefor mounted at the end of the arm, and a suitable power-transmitting system for operating the cutter. The base of the column of the machine fits in the shaft opening of the bucket-wheel, and in order to adapt the machine for finishing wheels of different sizes, interchangeable columns are employed.

When the wheel and machine are in operative position, the cutter-carrying arm extends parallel with the plane of the wheel and is adjustable laterally with respect to a radial position, so that the cutter may be adjusted to make a radial cut for any angle relatively to the plane of the wheel. The outer end of the arm is formed into a yoke, and the cutter carriage is mounted therein in a manner to permit of its being reciprocated for the working strokes, and also for being moved to different radial distances so as to adapt the machine for finishing the buckets of wheels of different radii. To set the cutter for finishing surfaces of any desired angle, the arm is adjusted on its axis as well as laterally. After once being adjusted to the proper angle, it need not be again adjusted during the finishing of the surfaces of the buckets on the same side of the wheel.

The working stroke of the cutter is under the control of an operator. For this purpose the carriage in which the tool is mounted, is connected with a hand lever arranged so as to be convenient to the operator,—preferably at the extremity of the arm. The cutter is intended to finish one surface of a bucket at a time, and after all of the surfaces of the buckets on one side of the wheel have been finished, the latter is turned over bodily or reversed with respect to the machine. This necessitates setting the cutter at a corresponding angle on the opposite side of a perpendicular to the plane of the wheel, as the angle of the bucket is reversed. To begin the cutting operation, the carriage is moved by the operator so that the cutter will occupy an initial position at the outer or tenon end of the bucket, and the cutter is then adjusted to make the proper depth of cut. One adjustment suffices for all of the bucket surfaces on one side of the wheel, which insures uniformity. The operator then presses the hand lever to cause the car-

riage to move inwardly with the cutter, toward the root of the bucket, cutting away the surface to the proper finish. When the cutter reaches the root of the bucket, the lever is reversed, whereby the cutter is withdrawn. The wheel or the machine is then turned in order to present the next bucket to the cutter, which is finished in the same manner. The operation is thus continued until the flat surfaces of the buckets on one side of the wheel are finished, whereupon the wheel is reversed and the machine adjusted to finish the other flat surfaces of the buckets.

For a more detailed understanding of the invention, reference is to be made to the following description, and the scope of the invention will be set forth in the appended claims.

In the accompanying drawings, which illustrate one embodiment of the invention, Figures 1 and 2 are perspective views, observed from different points, of a milling machine shown in operating position on a turbine bucket wheel; Fig. 3 is a longitudinal section 25 of a cutter carriage, and the adjacent portion of the arm supporting the same; Fig. 4 is a transverse section of the arm taken on line 4—4, Fig. 3; Fig. 5 is a similar section taken on line 5—5, Fig. 3, and showing the cutter carriage in elevation; Fig. 6 is a longitudinal section of the supporting column, showing the bearing construction of the machine; Fig. 7 is a plan view of the cutter-carrying arm and the means for adjusting the same laterally on the supporting column; Fig. 8 is a detail view of the cutter; and Fig. 9 is a view illustrating a section of a bucket wheel with certain of the buckets in finished and unfinished condition, and the cutter dressing 40 one of the buckets.

In the present instance, the bucket wheel 1 is shown blocked up on the table or work-holder in a horizontal and fixed position, with the milling machine mounted thereon in such a manner as to be revolved on the axis of the wheel for presenting the cutter successively to the buckets. The wheel may, however, be mounted on a suitable work-holder or table so as to turn, and it may turn 50 in either a horizontal or vertical plane. In the latter case the milling machine is mounted in fixed position, and the wheel is movably supported in proper relation thereto.

The machine is supported in position on a column or stub shaft 2, Fig. 6. This latter is provided at its base with shoulders 3 and 4 of different diameters, the lower one of which fits the shaft-opening 5 of the bucket wheel, while the upper one, being of larger diameter, rests upon the upper surface of the wheel and supports the column in fixed position. The column forms an interchangeable part 60 of the machine, bucket wheels having shaft-openings of different diameters requiring different sized columns. These latter differ

from one another, only in respect to the diameters of the shoulders 3 and 4, while the diameter of the shaft proper is uniform or standard for a single machine. On the column 2 a radial cutter-carrying arm 6 is mounted so as to pivot thereon, Figs. 1, 2 and 7. In order to permit the arm to turn, the same is mounted on the column 2 by means of a hollow column 7, which forms a rigid part of the arm, and which snugly fits the inner column so as to prevent any appreciable play on the latter and consequent vibration during the cutting stroke. The lower end of the hollow column rests upon anti-friction balls 8, Fig. 6, that are held in a race 9 formed on the shoulder 3. The arm extends from the supporting column in a direction substantially parallel with the plane of the wheel, and at its outer end is mounted a tool or cutter carriage 10. This end of the arm is formed into a yoke 11, Figs. 1 and 3, in which the cutter-carriage is held, and the longitudinal dimension of the opening of the yoke extends parallel with the axis of the arm, so that the carriage may be reciprocated in a direction to insure a radial cut.

The carriage comprises a head 12, which is bored in a direction at right angles to the axis of the arm, and contains a longitudinally movable sleeve 13, Figs. 3 and 5. In the sleeve 13 is arranged a rotating spindle 14 which carries the cutter or tool 15. The opposite sides of the head, which are preferably flat, engage between the two side-plates or webs 16 of the yoke, which form guides for the carriage. The carriage is held between these two webs by means of overhanging projections 17 at opposite sides of the head, that engage with the upper surfaces of the webs and a removable plate 18, secured to the under side of the head, which engages at its two opposite ends the under edges of the webs. The upper and lower edges of the webs are beveled and carefully finished, and the bearing surfaces of the overhanging projections 17 and of the plate 18 are correspondingly shaped to fit the said beveled edges of the webs. The under plate is secured in position by means of bolts 19 that screw into the head, and by the removal of which the head can be taken from the yoke. The cutter spindle 14 is adapted to move longitudinally in the head with the sleeve 13, and for this purpose it is held in the latter between a driving wheel or pulley 20, which is keyed at the upper end of the spindle, and the cutter 15 which screws on the lower end thereof, Fig. 3. The cutter screws home against a tapered collar 21, which in turn binds upon a soft fiber washer 22 between the collar and the lower end of the sleeve 13, Figs. 3 and 8. By this means the spindle is held from longitudinal movement in the sleeve, but is free to rotate therein. The cutter is self-retained on the screw- 130

thread of the spindle, as the direction of rotation for the cut operates to retain the cutter in place.

To adjust the sleeve and spindle in the head, the sleeve is provided with a rack 23, Fig. 3, with which meshes a pinion 24 that is adapted to be manually operated. The pinion is mounted on a shaft 25 journaled in lugs 26 that are formed on a tubular extension 27 of the head, Figs. 3 and 5. The tubular extension is provided with a slot 28, Fig. 3, registering with the rack and in which the pinion extends to mesh with the latter. The end 29 of the shaft of the pinion is squared so as to receive an operating crank. Thus by actuating the pinion the cutter-carrying spindle and sleeve may be moved longitudinally for adjusting the cutter with respect to the work. To reciprocate the carriage in the yoke for performing the cutting and return strokes, a manually-actuated lever 30 is arranged at the end of the arm and which connects with the head by a rod 31, Figs. 1 and 3. The rod extends through an opening in the end-plate 32 of the yoke, and its outer end is bifurcated to receive the lever 30 to which it is hinged. The lever is fulcrumed, as a lever of the first order, on a bracket 33, Figs. 1 and 2, and its outer end extends to a point convenient to the operator.

The cutter-carrying spindle may be driven in any desired manner. I prefer to rotate the same by means of an electric motor 34, which transmits power from its shaft pulley 35 to the wheel 20 on the upper end of the spindle by a belt or cable 36. The motor is secured on a top-plate 37 at the upper end of the hollow column 7, and is securely bolted in place, Figs. 1 and 2. Arranged in this manner the machine, and the power-transmitting mechanism therefor, constitute a single portable structure which is readily assembled on the work or bucket wheel and removed therefrom.

In order that the cutter may be set to finish surfaces of different angles, the driving belt is of sufficient length to permit the driving wheel on the cutter-carrying spindle to assume any position within the range of angular adjustment of the cutter. An idler is employed to take up the slack in the belt for the various adjustments and to maintain the belt in frictional engagement with the driving wheel. In the preferred manner of running the belt a distance pulley 38 is provided, Figs. 1 and 2, which is supported at the outer end of the cutter-carrying arm. The belt passes from the motor pulley around the distance pulley, and the driving wheel 20 is disposed between them, with the two lengths of the belt engaging with it at diametrically opposite points. The idler 39 is arranged so as to operate on the belt between the driving wheel and the distance pulley and with the parts in the posi-

tion shown, Fig. 2, the belt is running in the direction indicated by the arrow, Fig. 2. The driving wheel, the idler and distance pulley are arranged to rotate in a common plane, so that the alignment of the belt in the grooves of these several members may be insured. As the driving wheel is carried by the cutter spindle, any longitudinal adjustment of the latter for setting the cutter varies the relation of the driving wheel to the distance pulley and idler, so that the latter have to be adjusted also. For this purpose the distance pulley 38, Fig. 2, is mounted upon an arbor 40 that is adjusted along its axis in a socket 41 of a bracket 42 that is rigidly fixed to the outer end of the cutter-carrying arm. By this arrangement, the distance pulley may be raised or lowered for the change in position of the driving wheel. The idler is carried at the outer end of an arm or bracket 43 that is arranged on the sleeve of the cutter spindle so as to be movable therewith. The idler is thus maintained in the same plane with the driving wheel. It is angularly adjusted, however, on the sleeve, so as to take up the proper position for any particular angular adjustment of the cutter for varying the tension of the belt. To permit of this adjustment, the inner end of the bracket for the idler is provided with an eye 44 that fits around the sleeve and by means of a set-screw 45 carried by the eye and impinging on the sleeve the bracket is held in fixed position, Fig. 2.

When it is desired to finish the flat surfaces of buckets of different shapes or angles, it is necessary to accordingly set the cutter. This is done by adjusting the cutter-carrying arm about its axis. The point of adjustment is preferably between the hollow column and the inner end of the arm. It is to be noted that the perpendicular distance between the axis of the arm and the plane of the wheel is constant. Hence, in order to set the cutter to operate at different angles with respect to the plane of the wheel and yet insure its moving in a radial direction on the cutting stroke, the arm must be shifted in one direction or the other relatively to a radial position. Provision is thus necessary for axial and lateral adjustment of the arm. As shown in Figs. 1 and 7, a laterally adjustable carrier or support 46 is provided between the arm and the hollow column. The supporting arm is mounted on the carrier to be adjusted laterally therewith, and also to be turned axially. The column has secured to or cast integral therewith a dovetail guide-way 47, the center line of which is parallel with the plane of the wheel. The adjacent side of the carrier 46 is provided with a dovetail projection 47' which interlocks in the guide-way of the column. To move the carrier and the arm supported thereon a screw 48 is employed. This is supported in a laterally extending bracket 49 on the hollow

column, Figs. 2 and 7, and it turns freely in a bearing 51 in a bracket; but is prevented from moving therein in the direction of its axis. The inner end of the screw screws into a tapped opening of the block 52 bolted to the side of the carrier. The outer end of the screw is squared to receive a starting crank, whereby it is turned for moving the carrier laterally on the columns.

To adjustably secure the arm to the carrier the inner end is formed with a plate 53, Figs. 1, 2 and 7, which is provided with arc-shaped slots 54, and bolts 55 fitted with washers 56 extend through the slots and screw into the carrier to secure the arm to the latter. By loosening the bolts, the arm may be turned to set the cutter to any position desired, and by tightening the bolts the arm is secured in such position. To facilitate this adjustment, the upper surfaces of the carrier and the plate 53 are finished on the same radius, and a scale is provided on one or the other, as shown in Fig. 7. The length of the arc-shaped slots in the plate 53 determines the range of adjustment of the arm on its axis. These slots may be arranged to permit of the maximum adjustment of the arm, but in the present case, a second point of adjustment is provided for increasing the range. For this purpose the arm is made in two sections, an inner section 57 and an outer or yoke section 58, Figs. 1 and 7. The adjacent ends of the sections are formed with plates 59 and 60, and the adjustable connection between them is similar to that between the carrier 46 and the inner section of the arm. The sections are, therefore, independently adjustable.

In operation the arm is first adjusted on its axis to obtain the proper angle for the axis of the cutter-carrying spindle. After this is ascertained, the arm is adjusted laterally and the cutter-spindle adjusted longitudinally relatively to the work, and these adjustments are made by trial until a position of the cutter is arrived at that will insure a perfectly radial stroke for the cutter and a cut of the proper depth. The cutting stroke begins at the outer end of the bucket, and to make the stroke the operator presses the lever which moves the carriage with the cutter inwardly on one bucket at a time. When the root of the bucket is reached the stroke is reversed by the operator, whereby the cutter is returned to the starting position. The machine is then turned a sufficient distance to present the cutter to the next bucket to be in turn finished. In this manner the flat surfaces of all the buckets on one side of the wheel are finished successively. After they are finished, the machine is removed from the wheel by the shop-crane, the wheel turned over, and the machine replaced in position. As the flat surfaces on the second side of the wheel are disposed at a corre-

sponding angle to a perpendicular to the plane of the wheel, the arm has to be turned on its axis so that the cutter may operate at the proper angle. After its adjustment is made, the finishing operation continues as 70 before.

From the foregoing description it will be seen that with my machine the flat surfaces of the buckets are all finished at a uniform angle, and as no adjustment of 75 the cutter is necessary after beginning the operation of finishing, the buckets are preserved uniform in size.

The invention is shown in connection with a turbine wheel composed of a flat 80 disk with integral and radially extending buckets. When cast metal buckets are to be machined, the ring or segment thereof can either be mounted on the wheel that is to carry them or upon a suitable support. 85 This support may be in the form of a disk, ring or segment thereof, and should conform as closely as possible to the normal wheel. The machine may also be used to finish the so-called stationary or intermediate buckets. Suitable modifications may be made in the machine to permit of finishing buckets of other construction than that shown.

In accordance with the provisions of 95 the patent statutes, I have described the principle of operation of my invention, together with the apparatus which I now consider to represent the best embodiment thereof; but I desire to have it understood 100 that the apparatus shown is only illustrative, and that the invention can be carried out by other means.

What I claim as new and desire to secure by Letters Patent of the United States, is,— 105

1. In a machine of the character described, the combination of a column, means for supporting the column and the work in rotatable relation to each other, a carrier movably mounted on the column above 110 the work, means for adjusting the carrier rectilinearly in a direction transverse to the axis of the column in a plane parallel thereto, an arm adjustably attached to the carrier and projecting therefrom at right 115 angles to the plane of adjustment, means for angularly adjusting the arm about an axis transverse to the axis of the column, a tool holder carried by the outer end of the arm, means for adjusting the position 120 of the tool holder with respect to the arm, and a motor supported by the column which drives the tool.

2. In a machine of the character described, the combination of a supporting column, a 125 radial cutter-carrying arm revolvably mounted thereon to turn about the axis of the column, and means for adjusting the arm to occupy positions parallel to and on either side of a radial position.

3. In a machine of the character described, the combination of a supporting column having a base which is adapted to rest on the work, a tool-carrying arm revolubly supported on the column, a tool carriage arranged to reciprocate longitudinally on the arm, means for shifting the arm laterally and parallel to a radial position, and means for angularly adjusting the arm about its axis. 10
4. In a machine of the character described, the combination of a supporting column, means for supporting the work with respect to the axis of the column to permit of a relative turning movement, an arm carried by the column, means for shifting the arm laterally in a plane at right angles to the axis of the column, means for angularly adjusting the arm on its axis, and a tool-carriage operatively mounted on the arm. 15
5. In a machine of the character described, the combination of a hollow column which is adapted to be mounted on interchangeable supporting columns for work of different sizes, a radial arm arranged on the hollow column, means between the column and the arm which permits the latter to be adjusted laterally of and also around its axis, and a tool carriage operatively mounted on the arm. 20
6. In a machine of the character described, the combination of a supporting column suitable for work of a definite size, a hollow column adapted to fit the supporting column, a ball-bearing between the columns, an arm secured to the hollow column to rotate therewith, means between the arm and hollow column for adjusting the former in a lateral direction, means for adjusting the arm on its axis, and a tool-carriage on the arm which is adjustable and is adapted to be reciprocated axially of the arm. 25
7. In a machine for performing milling operations adjacent the edges of disk-like pieces of work, the combination of a supporting column at the center of the work, a hollow column assembled thereon, an antifriction bearing between the columns, an arm movably mounted on the hollow column which extends parallel to the plane of the work, a tool carriage mounted for longitudinal movement on the arm, a rotary tool carried by the carriage with its axis of rotation at right angles to said longitudinal movement, means for driving the tool, means for adjusting the arm together with the carriage and tool about an axis at right angles to the axis of the column to machine surfaces inclined at different angles and for adjusting them parallel to themselves after such angular adjustment to cause the longitudinal movement of the tool to be substantially radial with respect to the column, and a device for moving the carriage and tool along the arm. 30
8. In a machine of the character described, the combination of a supporting column, a cutter-carrying arm, a support between the arm and the column, a carrier between the arm and the support, means for adjusting the carrier laterally on the support, and means for adjusting the arm around its axis on the carrier. 35
9. In a machine of the character described, the combination of a supporting column, a hollow column assembled thereon, a dovetail way provided on the hollow column, a carrier movably supported in said way, means for adjusting the carrier laterally in the way, an arm secured to the carrier to move therewith, means for adjusting the arm about its axis on the carrier, and a tool carriage operatively mounted on the arm. 40
10. In a machine of the character described, the combination of a column adapted to be arranged centrally on the work to be finished, a radial arm supported thereon, a carrier between the column and the arm, a dovetail connection between the carrier and the column, an adjusting screw supported by the column for moving the carrier and the arm laterally on the column, means for permitting the arm to be adjusted axially on the carrier, and a tool carriage operatively mounted on the arm. 45
11. In a machine of the character described, the combination of a central supporting column, a radial arm mounted thereon to turn about the axis of the column, a tool carriage arranged on the arm which is movable longitudinally thereof, a cutter-carrying spindle mounted in the carriage which extends transversely to the axis of the arm and at an angle to the axis of the column, a cutter on the spindle, means for adjusting the spindle longitudinally in the carriage, and devices for adjusting the arm together with the carriage and spindle angularly about the axis of the arm and also laterally in a direction at right angles to the column to cause the longitudinal movement of the cutter to be in a substantially radial direction with respect to the supporting column. 50
12. In a machine of the character described, the combination of a central supporting column pivotally mounted to move about its axis, a radial arm mounted thereon, means for moving the arm transversely of the column, a cutter carriage mounted on the arm and adapted to move therewith about the axis of the column and also longitudinally of the arm, means carried by the arm for reciprocating the carriage, a cutter-carrying spindle mounted in the carriage, a cutter on the spindle, a source of power arranged on the column and movable therewith, and means for transmitting power from said source to the spindle. 55
13. In a machine of the character described, the combination of a supporting col- 60

- umn, a radial arm mounted thereon and composed of two sections which are independently adjustable about the same axis, a yoke formed on the outer section the axis of which 5 extends parallel to that of the arm, a carriage mounted on the yoke, means for reciprocating the carriage, a spindle mounted in the carriage with its axis extending transversely to that of the arm, a cutter on the 10 spindle, and means for rotating the cutter.
14. In a machine of the character described, the combination of a column, a radial arm adjustably mounted thereon, a yoke formed at the outer end of the arm, a carriage 15 movably mounted in the yoke, a rotating cutter-carrying spindle in the carriage, a manually actuated lever carried by the arm, and a connection between the lever and the carriage.
15. In a machine of the character described, the combination of a column, a radial arm adjustably mounted thereon which is provided with a yoke, means for adjusting the arm transversely of the column, a carriage 20 which is movable in the yoke in the direction of the axis of the arm, a sleeve in the carriage which extends transversely to the axis of the arm, a spindle rotatably mounted in the sleeve, a cutter on the spindle, means 25 for adjusting the spindle and sleeve together in the carriage, and a manually operated device carried by the arm for reciprocating the carriage and cutter during the cutting strokes.
16. A milling machine adapted to be 30 bodily supported and movably mounted on the work, the same comprising a column supported on the work, an adjustable cutter-carrying arm on the column, means for adjusting the arm laterally, a carriage mounted 35 for reciprocation on the arm, a cutter-carrying spindle in the carriage, a motor supported on the column, and a power transmitting device between the motor and the spindle for rotating the latter, said device includ-

ing means for permitting the arm and spindle 45 to be adjusted.

17. In a machine of the character described, the combination of a stationary support, an adjustable arm mounted to revolve about the axis of the support, means for adjusting the arm about its axis, means for shifting the arm laterally and parallel to its axis, a carriage longitudinally movable on the arm, a rotating cutter-carrying spindle adjustably mounted on the carriage, a driving wheel on the spindle, a motor supported to revolve with the arm, a belt driving connection between the wheel and motor, and means for maintaining said connection in operative relation to the wheel for all positions of adjustment of the cutter-carrying spindle.

18. In a machine of the character described, the combination of a supporting column, a radial arm which is revolvably mounted thereon and is capable of lateral and axial adjustment, a carriage on the arm which is adjustable therewith, means for reciprocating the carriage longitudinally of the arm, a cutter-carrying spindle on the carriage which 70 extends transversely of the arm and is longitudinally adjustable, a motor secured in fixed position on the supporting column, a shaft pulley for the motor, a distance pulley 75 adjustably supported on the arm, a driving wheel on the spindle which is movable therewith, an idler arranged in a common plane with the wheel and distance pulley and movable with the former, and a driving belt extending from the motor pulley to the distance 80 pulley and operatively engaging with the driving wheel and idler.

In witness whereof, I have hereunto set my hand this 15th day of April, 1905.

JOHN RIDDELL.
